UNITED STATES PATENT OFFICE.

ALLEN LOOMIS, OF ANN ARBOR, MICHIGAN.

AUTOMOBILE-ENGINE.

SPECIFICATION forming part of Letters Patent No. 787,581, dated April 18, 1905.

Application filed November 26, 1904. Serial No. 234,406.

To all whom it may concern:

Be it known that I, ALLEN LOOMIS, of Ann Arbor, in the county of Washtenaw and State of Michigan, have invented certain new and useful Improvements in Automobile-Engines, of which the following is a specification.

My invention relates to improvements in automobile-engines, especially those using steam; and the objects of the present invention are, first, to provide a frame for use in connection with my valve-gear (Serial No. 211,309, filed June 6, 1904; modified form shown in a former application for patent on an automobile-engine, Serial No. 223,240, filed September 3, 1904, and my power-transmission patent, No. 654,903, issued July 31, 1904) to enable the power to be applied directly to the rear axle without the intermediacy of any toothed wheels or other transmission devices, except the equalizing-gears; second, so to guide the movable parts of the frame as to avoid cramping the driving mechanism; third, to adapt the fixed portion of the frame to the application of a sectional dust-case of the general form shown and described in my application for a patent on an automobile-engine, Serial No. 223,240; fourth, to prevent dust and grit from entering around the movable parts, and, in general, to avoid unknown or excessive stresses, to insure cheapness of construction and ready accessibility of the working parts, and to keep the mechanism compact and adaptable to automobile-bodies of popular form, size, and height. I attain these objects by means of the mechanism illustrated in the accompanying drawings, in which—

Figure 1 is a plan view of a mechanism embodying my invention, the cylinder-casting being removed and some of the parts on the right-hand side being sectioned at 1 1, Fig. 2. Fig. 2 is a sectional elevation at 2 2, Fig. 1. Fig. 3 is a transverse section at 3 3, Fig. 1. Fig. 4 is a transverse section at 4 4, Fig. 1. Fig. 5 is a plan of a portion of the cross-head housing in section at 5 5, Fig. 2. Fig. 6 is an elevation of the left side of the rear part of a chassis with my engine fitted, the axle being sectioned at 6 6, Fig. 8. Fig. 7 is a sectional elevation of the crank-housing at 7 7, Fig. 1. Fig. 8 is a rear elevation. Figs. 9 to 12 illus-

trate a modified form of my invention. Fig. 9 is a perspective view looking down toward the left and rear, as indicated at 9, Fig. 10. Fig. 10 is a plan view of the rear part of a chassis with my engine fitted, a part being sectioned at 10 10, Fig. 11. Fig. 11 is a sectional elevation at 11 11, Fig. 10. Fig. 12 is an elevation of the left side of the rear part of an automobile with my engine fitted, the axle being sectioned at 12 12, Fig. 10.

Similar characters refer to similar parts throughout the several views.

I shall first describe the preferred form of my invention.

In the drawings, A A' are road-wheels fixed on the outboard ends of the axle-sections B B'. On the inboard ends of the axle-sections are fixed the internally-toothed wheels c c', having brake-drums formed on their peripheries and bearings on their hubs for the cranked member C.

The parts B C, &c., above mentioned are shown, described, and claimed in the patent and application referred to above. In the present case, however, the brake-lever c² extends downward from the brake-shaft, bringing the brake-rod c³ into compression instead of tension. c⁴ is a pedal for operating the brake.

d d' are the connecting-rods of the main driving-linkages. In order to avoid cramping when one road-wheel is lifted higher than the other relatively to the chassis, it is essential for the connecting-rods to be adapted to rotate slightly about the axes of the cylinders or other axes parallel thereto. As the form of valve-gear used precludes rotation of the cross-heads, the desired end is reached by using for the piston connections d² d³ a special form of ball-and-socket joint, the exact form of which will be fully described farther on in connection with the thrust-frame S. The upper and lower guides for each cross-head are made extra far apart in order to clear the connecting-rods when the axle is displaced vertically from its normal position.

d⁴ d⁵ are piston-rods, and d⁶ d⁷ are pistons. Only the left-hand piston is shown. (See Fig. 6.)

The valve-gear is of the form shown and described in the applications above referred to,

(Serial Nos. 211,309 and 223,240,) that shown on the first two sheets of the accompanying drawings being of the form adapted for use with the two **D** slide-valves. The characters referring to parts of the valve-gear are the same in the present application as in the applications above referred to. Only a few of the parts are here shown. (See Fig. 6.) 5
 10 9 is a reducing-link; 13, a rocking lever; 15, a rock-shaft; 17, a link-shaft, and 19 a curved link. The rocking levers are bent, as shown, to clear the reverse-shaft arms, which work in the spaces $e^9 e^{11}$, Figs. 1 and 3. In the present instance both reverse-shaft sections 15 are solid, as shown at e' , and work in holes in bosses $m m'$, formed on the side dust-case sections $M M'$. The right-hand lever e^9 extends upward from the reverse-shaft. The left-hand lever e^{10} extends downward and is connected by the link e^7 to the tumble-shaft arm e^5 . The two last-named parts are duplicated on the other side of the engine, the tumble-shaft e^{14} extending across the engine under the cylinders.
 20 25 $f' f'$ are side members of the chassis, and f^2 is an intermediate longitudinal member. The engine is secured to the latter two. f^3 is the rear transverse member. The chassis is mounted upon springs of customary form, as 30 at G .

A round beam H (best shown in Fig. 5) secures the forward end of the cross-head housing I to the chassis. The supporting force is concentrated at a single point of the cross-head housing by means of a ball-and-socket joint. The ball h , formed on the beam, is held in the cross-head housing by means of the threaded bushing i , having a part of the socket formed in its inboard end, and the 35 lock-nut i' . The rear end of the cross-head housing is secured to the chassis by bolts in the two lugs $i^2 i^3$. Thus three-point suspension of the cross-head housing is secured, which prevents twisting strains being transmitted to it from the chassis. The cylinder-casting i^4 is bolted to the crank-end cylinder-heads $i^5 i^6$, which are integral with the cross-head housing. The cylinders are slightly inclined to increase the road clearance under 40 them, but are substantially horizontal, inasmuch as they are approximately at right angles to the path of rise and fall of the axis.
 45 50

J is the bottom section of the dust-case.

K is the forward section of the dust-case.

55 In the present instance the top and bottom edges are inserted in grooves in the cross-head housing instead of being bolted to it.

L is the top section of the dust-case, which in the present instance is hinged to the cross-head housing at l and held shut by a single screw at l' .

$M M' M^2 M^3$ are the side sections of the dust-case, which are supplemented by the bases of the pump-barrel castings $N N'$.

60 65 Around the rear end of the cross-head hous-

ing is formed a lip i^7 . To this is secured by the seizing o the forward end of the sleeve O , which is made of leather, rawhide, enamel-cloth, or other pliable material, which is dust-proof and also preferably oil-tight. The seizing 70 is preferably of tarred marline. The rear end of the sleeve is similarly seized at o' to a lip on the forward side of the crank-housing.

$P P'$ are the sections of the crank-housing, which are joined at the center line by the fourteen bolts $p p$, &c. In the outboard ends of the crank-housing are brazed the tubular axle-housings $p^1 p^2$, containing outboard axle-bearings $p^3 p^4$ and carrying spring-seat bearings $p^5 p^6$ and also in the case of the longer 80 housing a thrust-rod connection p^7 . The inboard axle-bearings are within the crank-housing, as shown at p^8 , Fig. 1. The essential requirement of the spring-seat bearings is that they enable the spring-seats to rotate 85 slightly about the axis of the tubular housings or about a line parallel to it. The ball-and-socket joints here shown have the advantage also of reducing the twisting strains produced in the springs when one is compressed 90 more than the other.

A hand-hole is formed in each section of the crank-housing especially to facilitate adjustment of the brake-bands. These hand-holes are fitted with covers $p^9 p^{10}$, each secured by 95 four screws p^{11} . Lips $p^{12} p^{13}$, formed on the rear of the crank-housing sections, serve as guides for the roller r , which takes the part of the block in a sliding block-linkage. Said roller turns on a pin r' , whose axis is midway 100 between the axes of the cylinders and parallel to them. The pin is fixed relatively to the chassis by means of the struts $R R'$.

The thrust-frame S serves to maintain the proper distance between the crank-shaft and 105 cylinders to transmit to the chassis the greater part of the driving effect of the wheels and to resist the tendency of the crank-housing to rotate with the axle-sections when the brakes are applied. The greatest stresses are, however, produced in the thrust-frame by the reaction of the connecting-rods. To resist this, it is necessary to have very strong and direct connections at the ends. Fixed in the rear 110 end of the thrust-frame is a pin s , the ends of which fit into bushings $s' s'$, clamped between the crank-housing sections. The forward end of the thrust-frame is connected to the cross-head housing by means of a special ball-and-socket joint. The bearing-surface is in shape 115 a narrow zone of a sphere. The bushing s^2 , inserted in the eye of the thrust-frame, is the exterior part. It is relieved at top and bottom, as best shown in Fig. 2, to enable the gudgeon s^3 to be inserted edgewise. The 120 gudgeon is then revolved into position and secured between the jaws $s^4 s^5$, formed on the cross-head housing by means of the screw s^6 . As mentioned above, the piston connections 125 $d^2 d^3$ are of the same form.

In order to minimize the tendency of the connecting-rod thrust to produce rotation of the crank-housing and thrust-frame about the forward thrust-frame connection s^3 , it is desirable to locate said connection s^3 as near as possible to the mid-position of the connecting-rod gudgeons. At the same time it is necessary that the jaws s^4 s^4 clear the rocking levers 13 and 14. (14 not shown.) I prefer to 10 locate the jaws s^4 s^4 forward of the rocking levers, as shown.

The thrust-rod T, which is of customary form, supplements the action of the thrust-frame in transmitting to the chassis the driving effect of the road-wheels. The forward end is pivotally connected to an extension t of the chassis, which brings the axis of the pivot into coincidence, as viewed from the side, with the axis of the forward thrust-frame connection. 20

With the proportions shown in the drawings when the crank-case is displaced vertically until the roller r comes into contact with the top or bottom of the guiding-lips p^{12} p^{13} the effect is to lengthen the stroke about three-fourths of one per cent. at the crank end, which is insignificant. The head-end limit of the stroke remains practically unchanged. 25

The greatest tendency to cramp the crank-pin bearings or the roller r occurs when one of the thrust members S T is in its normal or mid position and the other is raised or depressed to the full extent indicated in the preceding paragraph. In this case one of the thrust connections p^7 s^1 is carried forward of the other, so that the axle does not make a right angle with the axis of the engine. The magnitude of this angle in the extreme case, with the proportions shown in the drawings, 30 is about twenty-eight minutes, which is the extreme cramping angle for the roller r . For the crank-pins this may be augmented to thirty-five minutes, because the crank-pins are forward of the point guided by the roller r and are therefore subject to an additional lateral displacement. The above-named angles are reduced by one-half if the vertical displacement of the thrust connection is reduced by about one-fourth. The connecting- 45 rods are long and slender and capable of considerable deflection under a light deflecting force. Because of the above facts it is considered unnecessary to provide knuckle or universal joints at the crank ends of the connecting-rods. 55

In the modified form (illustrated in Figs. 9 to 12) the crank-shaft, equalizing-gear, brakes, driving-linkages, valve-gear, engine-frame, dust-case, pump, flexible sleeve, axle-housing, 60 and thrust-frame are exactly as illustrated on larger scales in my previous application, Serial No. 211,309. The crank-housing is the same, except for the addition of a boss p^{14} , in which is fixed the pin r' for the roller r . In 65 this instance the roller-guide p^{12} is secured to

the chassis, being braced by the diagonal rod r^3 , and the motion of the roller is cushioned at the extreme positions by means of the rubber bumpers r^4 r^4 , which are fixed in the guide. This leaves the inside of the crank-housing 70 more accessible; but on account of the eccentricity of the guided point necessitates knuckle-joints d^8 (not shown) and d^9 in the connecting-rods. The equalizing-gears are incased by the crank-disks and the shells of 75 the internal gears, and the crank-housing is left entirely open at the rear. The flexible sleeve O has more fullness than in the preferred form and is separately seized at o^2 o^3 o^4 to the thrust-frame and connecting rods. 80 The arrangement of dust-case sections, pump, and crosshead-housing supports are also different. In this design the jaws s^4 s^4 are located in the rear of the rocking levers instead of forward, as in the preferred form. 85 A single reverse-shaft e^{25} is used, crossing the chassis immediately forward of the boiler f^4 , which is located on the same side of the vehicle as the reverse-lever e^{26} . f^5 is a door in the body for access to the engine. In the 90 modified form the spring-seat bearings p^5 p^6 are cylindrical instead of spherical, and the springs G G are semi-elliptic instead of elliptic. It is obvious from the two sets of plans accompanying this specification that the form 95 and general arrangement of the different parts may be varied widely without departing from the spirit of my invention.

I am aware of Patent No. 652,942, granted to G. E. Whitney on July 3, 1900; but the 100 "motor" claimed by him comprises, as shown in his drawings, vertical cylinders, bell-crank levers, and an extra pair of connecting-rods to convert the motion of the pistons into horizontal motion. His connecting-rods universally jointed at both ends are located between his distance-rods, and his brackets secured to the boiler for resisting the reaction of the connecting-rods are inherently weak, and the location of the pivots on same is such 110 as to produce great vertical vibration of the vehicle-body. In disclosing my invention, on the other hand, I have shown how to minimize this effect. By a careful consideration of the stresses involved I have been enabled to 115 dispense with Whitney's complicated motor and substitute therefor the simpler leakage and more-direct horizontal cylinders. I have also invented a suitable valve-gear, an item which appears to have been heretofore neglected. 120

I claim—

1. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle 125 housings, a chassis mounted on springs, sub- 130

stantially horizontal cylinders secured to the chassis, pistons working in the cylinders, driving connecting-rods from the pistons to the crank-pins, and a thrust member intermediate the connecting-rods and adapted to maintain a substantially constant distance between the crank-housing and the cylinders, while permitting the road-wheels to rise and fall independently of each other.

10 2. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle 15 housings, a chassis mounted on springs, substantially horizontal cylinders secured to the chassis, pistons working in the cylinders, driving connecting-rods from the pistons to the crank-pins, a thrust member intermediate the connecting-rods and adapted to maintain a substantially constant distance between the crank-housing and the cylinders, while permitting the road-wheels to rise and fall independently of each other, and a linkage adapted to restrict motion of the crank-housing across the chassis.

3. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle 30 housings, a chassis mounted on springs, substantially horizontal cylinders secured to the chassis, pistons working in the cylinders, driving connecting-rods from the pistons to the crank-pins, a thrust member intermediate the connecting-rods and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing adapted to restrict motion of the crank-housing across the chassis.

4. In combination in an automobile, road-wheel axle-sections, each of which is driven, a multiple-cranked driving member intermediate the axle-sections, and having with them a common axis of rotation, a differential gear 55 making driving connection from said cranked member to the axle-sections, crank and axle housings, a chassis mounted on springs, substantially horizontal cylinders secured to the chassis, pistons working in the cylinders, driving connecting-rods from the pistons to the crank-pins, a thrust member intermediate the connecting-rods and adapted to maintain a substantially constant distance between the crank-housing and the cylinders, while permitting the road-wheels to rise and fall independently of each

mitting the road-wheels to rise and fall independently of each other, a guide and a bearing, one fixed relatively to the chassis, the other fixed relatively to the crank-housing, and a movable part interacting between the guide and the bearing and adapted to restrict motion of the crank-housing across the chassis.

5. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle 70 housings, a chassis mounted on springs, substantially horizontal cylinders, fixedly secured to the chassis and articulately connected to the crank-housing, pistons working in the cylinders, driving connecting-rods from the pistons to the crank-pins, and a thrust member 75 intermediate the connecting-rods jointed to the cylinders and adapted to maintain a substantially constant distance between the crank-housing and the cylinders while permitting the road-wheels to rise and fall independently 80 of each other.

6. In combination in an automobile, road-wheel axle-sections, each of which is driven, a multiple-cranked driving member intermediate the axle-sections, and having with them 95 a common axis of rotation, a differential gear making driving connection from said cranked member to the axle-sections, crank and axle housings, a chassis mounted on springs, substantially horizontal cylinders fixedly secured 100 to the chassis and articulately connected to the crank-housing, pistons working in the cylinders, driving connecting-rods from the pistons to the crank-pins, and a thrust member 105 intermediate the connecting-rods universally jointed to the cylinders and adapted to maintain a substantially constant distance between the crank-housing and the cylinders, while permitting the road-wheels to rise and fall independently 110 of each other.

7. In combination in an automobile, road-wheel axle-sections, each of which is driven, a multiple-cranked driving member intermediate the axle-sections, and having with them 115 a common axis of rotation, a differential gear making driving connection from said cranked member to the axle-sections, crank and axle housings, a chassis mounted on springs, substantially horizontal cylinders fixedly secured to the chassis and articulately connected to the 120 crank-housing, pistons working in the cylinders, driving connecting-rods from the pistons to the crank-pins, a thrust member intermediate the connecting-rods jointed to the cylinders and adapted to maintain a substantially 125 constant distance between the crank-housing and the cylinders, while permitting the road-wheels to rise and fall independently of each

other, and a linkage adapted to restrict motion of the crank-housing across the chassis.

8. In combination in an automobile, road-wheel axle-sections, each of which is driven, 5 a multiple-cranked driving member intermediate the axle-sections, and having with them a common axis of rotation, a differential gear making driving connection from said cranked member to the axle-sections, crank and axle 10 housings, a chassis mounted on springs, substantially horizontal cylinders fixedly secured to the chassis and articulately connected to the crank-housing, pistons working in the cylinders, driving connecting-rods from the pistons 15 to the crank-pins, a thrust member intermediate the connecting-rods universally jointed to the cylinders and adapted to maintain a substantially constant distance between the crank-housing and the cylinders, while permitting the road-wheels to rise and fall independently of each other, and a linkage adapted to restrict motion of the crank-housing across the chassis.

9. In combination in an automobile, road-wheel axle-sections, each of which is driven, 25 a multiple-cranked driving member intermediate the axle-sections and having with them a common axis of rotation, a differential gear making driving connection from said cranked member to the axle-sections, crank and axle 30 housings, a chassis mounted on springs, substantially horizontal cylinders fixedly secured to the chassis and articulately connected to the crank-housing, pistons working in the cylinders, driving connecting-rods from the pistons 35 to the crank-pins, a thrust member intermediate the connecting-rods jointed to the cylinders and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing, adapted to restrict motion of the crank-housing across the chassis.

40 10. In combination in an automobile, road-wheel axle-sections, each of which is driven, a multiple-cranked driving member intermediate the axle-sections and having with them 45 a common axis of rotation, a differential gear making driving connection from said cranked member to the axle-sections, crank and axle 50 housings, a chassis mounted on springs, substantially horizontal cylinders fixedly secured to the chassis and articulately connected to the crank-housing, pistons working in the cylinders, driving connecting-rods from the pistons 55 to the crank-pins, a thrust member intermediate the connecting-rods universally jointed to the cylinders and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing, adapted to restrict motion of the crank-housing across the chassis.

60 bearing, one fixed relatively to the chassis, 65 the other fixed relatively to the crank-housing adapted to restrict motion of the crank-housing across the chassis.

11. In combination in an automobile, road-wheel axle-sections, each of which is driven, 7c a multiple-cranked driving member intermediate the axle-sections and having with them a common axis of rotation, a differential gear making driving connection from said cranked member to the axle-sections, crank and axle 75 housings, a chassis mounted on springs, substantially horizontal cylinders fixedly secured to the chassis and articulately connected to the crank-housing, pistons working in the cylinders, driving connecting-rods from the pistons 8c to the crank-pins, a thrust member intermediate the connecting-rods jointed to the cylinders and adapted to maintain a substantially constant distance between the crank-housing and the cylinders, while permitting the road-wheels to rise and fall independently of each other, a guide and a bearing, one fixed relatively to the chassis, the other fixed relatively to the crank-housing, and a movable part interacting between the guide and the bearing 90 and adapted to restrict motion of the crank-housing across the chassis.

12. In combination in an automobile, road-wheel axle-sections, each of which is driven, 95 a multiple-cranked driving member intermediate the axle-sections and having with them a common axis of rotation, a differential gear making driving connection from said cranked member to the axle-sections, crank and axle 100 housings, a chassis mounted on springs, substantially horizontal cylinders fixedly secured to the chassis and articulately connected to the crank-housing, pistons working in the cylinders, driving connecting-rods from the pistons 105 to the crank-pins, a thrust member intermediate the connecting-rods, universally jointed to the cylinders and adapted to maintain a substantially constant distance between the crank-housing and the cylinders, while permitting the road-wheels to rise and fall independently of each other, a guide and a bearing, one fixed relatively to the chassis, the other fixed relatively to the crank-housing, and a movable part interacting between the guide and the bearing 110 and adapted to restrict motion of the crank-housing across the chassis.

13. In combination in an automobile, road-wheel axle-sections, each of which is driven, a multiple-cranked driving member intermediate the axle-sections, and having with them 115 a common axis of rotation, a differential gear making driving connection from said cranked member to the axle-sections, crank and axle 120 housings, a chassis mounted on springs, substantially horizontal cylinders fixedly secured to the chassis and articulately connected to the crank-housing, pistons working in the cylinders, driving connecting-rods from the pistons 125

to the crank-pins, and thrust mechanism jointed to the cylinders and adapted to maintain a substantially constant distance between the crank-housing and the cylinders, while permitting the road-wheels to rise and fall independently of each other.

14. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism jointed to the cylinders and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing adapted to restrict motion of the crank-housing across the chassis.

15. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism jointed to the cylinders and adapted to maintain a substantially constant distance between the crank-housing and the cylinders, while permitting the road-wheels to rise and fall independently of each other.

16. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism universally jointed to the cylinders and adapted to maintain a substantially constant distance between the crank-housing and the cylinders, while permitting the road-wheels to rise and fall independently of each other, and a linkage adapted to restrict motion of the crank-housing across the chassis.

17. In combination in an automobile, road-

wheel axle-sections, each of which is driven, a multiple-cranked driving member intermediate the axle-sections, and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism jointed to the cylinders and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing adapted to restrict motion of the crank-housing across the chassis.

18. In combination in an automobile, road-wheel axle-sections, each of which is driven, a multiple-cranked driving member intermediate the axle-sections, and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism universally jointed to the cylinders and adapted to maintain a substantially constant distance between the crank-housing and the cylinders, while permitting the road-wheels to rise and fall independently of each other, and a guide and a bearing, one fixed relatively to the chassis, the other fixed relatively to the crank-housing adapted to restrict motion of the crank-housing across the chassis.

19. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism jointed to the cylinders and adapted to maintain a substantially constant distance between the crank-housing and the cylinders, while permitting the road-wheels to rise and fall independently of each other, a guide and a bearing, one fixed relatively to the chassis, the other fixed relatively to the crank-housing, and a movable part interacting between the guide and the bearing and adapted to re-

strict motion of the crank-housing across the chassis.

20. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle 50 housings, a chassis mounted on springs, substantially horizontal cylinders fixedly secured to the chassis and articulately connected to the crank-housing, pistons working in the cylinders, driving connecting-rods from the pistons to the crank-pins, thrust mechanism universally jointed to the cylinders and adapted to maintain a substantially constant distance between the crank-housing and the cylinders, while permitting the road-wheels to rise and fall independently of each other, a guide and a bearing, one fixed relatively to the chassis, the other fixed relatively to the crank-housing, and a movable part interacting between the guide and the bearing and adapted to restrict motion of the crank-housing across the chassis.

21. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle 50 housings, a chassis mounted on springs, substantially horizontal cylinders fixedly secured to the chassis, pistons working in the cylinders, driving connecting-rods from the pistons to the crank-pins, and thrust mechanism adapted to maintain a substantially constant distance between the crank-housing and the cylinders, while permitting the road-wheels to rise and fall independently of each other.

22. In combination in an automobile, road-wheel axle-sections, each of which is driven, a multiple-cranked driving member intermediate the axle-sections and having with them a common axis of rotation a differential gear making driving connection from said cranked member to the axle-sections, crank and axle 50 housings, a chassis mounted on springs, substantially horizontal cylinders fixedly secured to the chassis, pistons working in the cylinders, driving connecting-rods from the pistons to the crank-pins, thrust mechanism adapted to maintain a substantially constant distance between the crank-housing and the cylinders, while permitting the road-wheels to rise and fall independently of each other, and a linkage adapted to restrict motion of the crank-housing across the chassis.

23. In combination in an automobile, road-wheel axle-sections, each of which is driven, a multiple-cranked driving member intermediate the axle-sections and having with them a common axis of rotation, a differential gear

making driving connection from said cranked member to the axle-sections, crank and axle housings, a chassis mounted on springs, substantially horizontal cylinders fixedly secured to the chassis, pistons working in the cylinders, driving connecting-rods from the pistons to the crank-pins, thrust mechanism adapted to maintain a substantially constant distance between the crank-housing and the cylinders, while permitting the road-wheels to rise and fall independently of each other, and a guide and a bearing, one fixed relatively to the chassis, the other fixed relatively to the crank-housing adapted to restrict motion of the crank-housing across the chassis.

24. In combination in an automobile, road-wheel axle-sections, each of which is driven, a multiple-cranked driving member intermediate the axle-sections and having with them a common axis of rotation, a differential gear 85 making driving connection from said cranked member to the axle-sections, crank and axle housings, a chassis mounted on springs, substantially horizontal cylinders fixedly secured to the chassis, pistons working in the cylinders, driving connecting-rods from the pistons to the crank-pins, thrust mechanism adapted to maintain a substantially constant distance between the crank-housing and the cylinders, while permitting the road-wheels to rise and fall independently of each other, a guide and a bearing, one fixed relatively to the chassis, the other fixed relatively to the crank-housing, and a movable part interacting between the guide and the bearing and adapted to restrict motion of the crank-housing across the chassis.

25. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle 95 housings, a chassis mounted on springs, substantially horizontal cylinders secured to the chassis, pistons working in the cylinders, driving connecting-rods from the pistons to the crank-pins, a thrust member intermediate the connecting-rods and adapted to maintain a substantially constant distance between the crank-housing and the cylinders, while permitting the road-wheels to rise and fall independently of each other, and a flexible sleeve closing the crank end of the space occupied by the piston connections.

26. In combination in an automobile, road-wheel axle-sections, each of which is driven, a multiple-cranked driving member intermediate the axle-sections and having with them 125 a common axis of rotation, a differential gear making driving connection from said cranked member to the axle-sections, crank and axle housings, a chassis mounted on springs, substantially horizontal cylinders secured to the

chassis, pistons working in the cylinders, driving connecting-rods from the pistons to the crank-pins, a thrust member intermediate the connecting-rods and adapted to maintain a substantially constant distance between the crank-housing and the cylinders, while permitting the road-wheels to rise and fall independently of each other, and a flexible sleeve closing the crank end of the space occupied by the piston connections and the head end of the crank-housing.

27. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articularly connected to the crank-housing, pistons working in the cylinders, driving connecting-rods from the pistons to the crank-pins, a thrust member intermediate the connecting-rods jointed to the cylinders and adapted to maintain a substantially constant distance between the crank-housing and the cylinders, while permitting the road-wheels to rise and fall independently of each other, and a flexible sleeve closing the crank end of the space occupied by the piston connections.

28. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articularly connected to the crank-housing, pistons working in the cylinders, driving connecting-rods from the pistons to the crank-pins, a thrust member intermediate the connecting-rods jointed to the cylinders and adapted to maintain a substantially constant distance between the crank-housing and the cylinders, while permitting the road-wheels to rise and fall independently of each other, and a flexible sleeve closing the crank end of the space occupied by the piston connections and the head end of the crank-housing.

29. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housing, a chassis mounted on springs, substantially horizontal cylinders fixedly secured to the chassis and articularly connected to the crank-housing, pistons working in the cylin-

ders, driving connecting-rods from the pistons to the crank-pins, a thrust member intermediate the connecting-rods universally jointed to the cylinders and adapted to maintain a substantially constant distance between the crank-housing and the cylinders, while permitting the road-wheels to rise and fall independently of each other, and a flexible sleeve closing the crank end of the space occupied by the piston connections.

30. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articularly connected to the crank-housings, pistons working in the cylinders, driving connecting-rods from the pistons to the crank-pins, a thrust member intermediate the connecting-rods universally jointed to the cylinders and adapted to maintain a substantially constant distance between the crank-housing and the cylinders, while permitting the road-wheels to rise and fall independently of each other, and a flexible sleeve closing the crank end of the space occupied by the piston connections and the head end of the crank-housing.

31. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articularly connected to the crank-housing, pistons working in the cylinders, driving connecting-rods from the pistons to the crank-pins, thrust mechanism jointed to the cylinders and adapted to maintain a substantially constant distance between the crank-housing and the cylinders, while permitting the road-wheels to rise and fall independently of each other, and a flexible sleeve closing the crank end of the space occupied by the piston connections.

32. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articularly connected to the crank-housing, pistons working in the cylinders, driving connecting-rods from the pistons to the crank-pins, thrust mechanism jointed

to the cylinders and adapted to maintain a substantially constant distance between the crank-housing and the cylinders, while permitting the road-wheels to rise and fall independently of each other, and a flexible sleeve closing the crank end of the space occupied by the piston connections and the head end of the crank-housing.

33. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism universally jointed to the cylinders and adapted to maintain a substantially constant distance between the crank-housing and the cylinders, while permitting the road-wheels to rise and fall independently of each other, and a flexible sleeve closing the crank end of the space occupied by the piston connections.

34. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis and articulately connected to the crank-housing, pistons working in the cylinders, driving connecting-rods from the pistons to the crank-pins, thrust mechanism universally jointed to the cylinders and adapted to

maintain a substantially constant distance between the crank-housing and the cylinders, while permitting the road-wheels to rise and fall independently of each other, and a flexible sleeve closing the crank end of the space occupied by the piston connections and the head end of the crank-housing. 45

35. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis, pistons working in the cylinders, driving connecting-rods from the pistons to the crank-pins, thrust mechanism, and a flexible sleeve closing the crank end of the space occupied by the piston connections. 50

36. In combination in an automobile, road-wheel axle-sections, each of which is driven, a multiple-cranked driving member intermediate the axle-sections and having with them a common axis of rotation, a differential gear making driving connection from said cranked member to the axle-sections, crank and axle housings, a chassis mounted on springs, substantially horizontal cylinders fixedly secured to the chassis, pistons working in the cylinders, driving connecting-rods from the pistons to the crank-pins, thrust mechanism, and a flexible sleeve closing the crank end of the space occupied by the piston connections and the head end of the crank-housing. 55

In testimony whereof I have affixed my signature in presence of two witnesses.

ALLEN LOOMIS.
